UNITED STATES PATENT OFFICE.

JOSEPH C. CATLETT AND EDWARD F. NELSON, OF EAST ORANGE, NEW JERSEY, AS
SIGNORS TO I. R. NELSON CO., A CORPORATION OF NEW JERSEY.

HOLDING DEVICE FOR COILS.

Application filed October 4, 1921. Serial No. 505,311.

To all whom it may concern:

Be it known that we, JOSEPH C. CATLETT and EDWARD F. NELSON, both citizens of the United States, and residents of East Orange, 5 in the county of Essex and State of New Jersey, have invented new and useful Improvements in Holding Devices for Coils, of which the following is a specification.

This invention relates to reels or holders 10 for coils of wire, cord or the like, one object of the invention being to provide a device of this character embodying novel and improved features of construction which will prevent accidental unwinding of the wire or 15 cord and from which a desired amount of wire or cord can be unwound without the possibility of the remainder of the same unwinding itself or becoming entangled by springing off the reel when the end is loosened or when the reel is dropped or laid 20 down.

Further objects of the invention are to provide a reel or holder of the character described which at all times positively prevents 25 accidental unwinding of the wire or string and permits the wire or string to be freely unwound therefrom a single strand at a time by an operator and without bodily removing the coil from the reel; to provide 30 such a reel having adjustable holding means adapted to be adjusted to enable a coil of wire or string to be bodily applied to the reel and the wire unwound in any desired length without disturbing the remainder of the 35 coil; to provide a reel comprising a substantially disk-like body having a plurality of radially disposed members at its side to receive a coil of wire or string between themselves and said body; to provide such a reel 40 having the clips so arranged as to permit the wire to be unwound only one convolution at a time; to provide a reel comprising a disk-like body having a plurality of radially disposed clips on its side to receive a coil between 45 said clips and said body, said clips permitting a single strand of wire to be pulled between their outer ends and said body to unwind the same from or wind it upon said coil; to provide such a reel in 50 which the clips are resilient and adjustably secured at their inner ends to said body so that they can be swung inwardly of the body to permit a coil to be laid thereon and sprung

upwardly over the coil as they are swung into normal position to hold the coil; to so 55 construct and secure the clips to the body that the ends of the wire or coil can be clamped between them and the body; to provide the clips with cutting notches whereby the wire or string can be easily cut or broken 60 off the coil at a desired point; to provide such a reel which can be easily carried and handled, and which is simple and inexpensive; and to obtain other results and advantages as may be brought out by the following 65 description.

Referring to the accompanying drawings in which like numerals of reference indicate the same parts throughout the several views,

Figure 1 is a front elevation of a reel or 70 holder for wire and the like constructed in accordance with our invention;

Figure 2 is a side elevation thereof;

Figure 3 is a transverse sectional view taken on line 2-2 of Figure 1 and showing 75 a coil of wire in position on the reel;

Figure 4 is a view similar to Figure 2 showing a modified construction of the reel, and

Figure 5 is a front elevation of a modified 80 form of the invention.

In the embodiment of our invention shown in Figures 1-3 inclusive, the reference character 1 designates the substantially circular disk-like body of the reel which is formed 85 of suitable stiff material, such for instance as sheet metal, and has secured to one side thereof a plurality of coil holding or retaining clips 2.

The clips 2 are preferably formed of 90 strips of resilient sheet metal and have one end thereof substantially flat and straight as indicated at 3 and the other end thereof bent into a substantially semi-circular shape as at 4. The clips are preferably pivotally 95 secured to one side of the body 1 by means of rivets or similar fastening members 5 which pass through the ends 3 of the clips and the body, the said clips being radially arranged on the body and substantially 100 equidistantly spaced circumferentially thereof. The outer curved ends 4 of the clips are normally arranged with their extremities substantially flush with the periphery of the body, and the said extremities bear against 104 or are slightly spaced from the side of the

- disk, all as clearly shown in Figures 1 and 2. The curved portions 4 of the clips are adapted to receive between themselves and the body 1 a coil 6 of wire, cord or the like, and for the purpose of applying the coil to the reel the clips 2 may be swung about their pivots 5 into the positions indicated by dotted lines on Figure 1 so as to move the portions 4 thereof inwardly of the body.
- 10 This provides a clearance for the application of the coil 6, and after the coil is placed upon the body the clips 4 are swung upwardly over the coil and into the position shown in Figures 1 and 3. The inner extremity 7 of the wire or cord in the coil 6 is forced beneath the flat portion 3 of one of the clips, as shown in Figure 5, at the outer side of the pivot 5, and the free end 8 of the wire is pulled under the inner end 20 of another clip so that the ends of the coil are positively held against unwinding. When it is desired to obtain a length of the wire or cord from the coil it is merely necessary to pull the free end 8 from beneath 25 the corresponding clip and outwardly between the outer extremity of the clip and the body, the extremity of the clip springing outwardly as the wire is pulled from beneath the same. When the desired length 30 of wire has been thus unwound from the reel, the wire is slipped beneath the portion 3 of one of the clips 2 at the point where it is desired to sever the wire, after which the wire may be broken or twisted off. To 35 facilitate in breaking or cutting the wire, the portions 3 of the clips may be provided with cutting notches 9 into which the wire may be pulled to sever the same.
- With this construction it will be seen that 40 the coil is positively held on the reel by the clips 2 and that the clips permit the wire to be unwound only one convolution at a time, thereby eliminating the possibility of the remainder of the coil springing off the reel 45 or accidentally unwinding when the reel is dropped or laid down. The clips also permit the wire to be unwound without the necessity of bodily removing the coil from the reel as is necessary in some constructions.
- 50 To facilitate in unwinding the wire or cord, the body 1 may be provided with a substantially centrally located handle 10 which may be swivelled in the body so that the body may rotate thereon.
- 55 A modified form of the reel is shown in Figure 4 of the drawings in which a series of clips 2 is arranged on each side of the body 1, thereby enabling the reel to hold two coils of wire or cord. The operation of this form 60 of the invention is the same as above described.
- In Figure 5 we have shown a construction 65 in which the body 1 instead of being circular is provided with a plurality of radially projecting arms 11 on which the
- clips 2 are secured. This construction results in a saving of material in the body and also facilitates in handling the reel in that the finger of the operator may be inserted between the coil and the edge of the body 70 between the arms 11 thereof.
- While the clips have been described as pivotally mounted on the body so as to be adjustable to receive a previously wound coil, we also contemplate fixedly connecting 75 said clips to the body, as by spot welding, in which case the material would be wound directly on the reel.
- In all of the forms of the invention above described, it will be noted that the clips 2 form a seat for the coil of wire or like material, the outer ends of the clips forming between themselves and the body a restricted outlet to permit the passage of one thickness 80 of the wire in unwinding the same from or winding it upon the coil. It will also be noted that the breaking or severing of a length of wire from the coil by means of the cutting notches 9, and the clamping of the free end of the coil beneath the end 3 of the 85 clip are performed simultaneously.
- While we have shown one possible embodiment of our invention, it will be understood that this is for the purpose of illustrating the principles thereof only, and that many modifications and changes can be made in the detail construction of the body and holding clips of the reel without departing from the spirit or scope of the invention. Therefore, we do not desire to be understood 90 as limiting ourselves except as required by the following claims when construed in the light of the prior art.
- Having thus described the invention, what we claim is:
1. A device of the character described including a body having a plurality of radially disposed resilient clips thereon to receive a coil of wire or like material, the said clips being normally disposed to prevent said material from accidentally unwinding and the outer ends thereof being adapted to yield to permit said material to be unwound one thickness at a time.
2. A device of the character described including a flat sheet metal body having a plurality of resilient sheet metal radially disposed clips thereon to receive a coil of wire or like material, the said clips being normally disposed to prevent said material from accidentally unwinding and the outer ends thereof being adapted to yield to permit said material to be unwound one thickness at a time.
3. A device of the character described including a flat sheet metal body, and a plurality of radially disposed resilient sheet metal clips having one end permanently secured to said body and their other ends free from said body, said clips being adapted to

receive between themselves and said body a coil of wire or like material, the free ends of said clips being normally spaced from said body a distance less than one thickness of 5 said material.

4. A device of the character described, including a body, and a plurality of resilient clips mounted at one end on said body and adapted to receive between their other ends 10 and said body a coil of wire or like material, said second mentioned ends of the clips yielding away from said body to permit the passage of one thickness of said material between them and said body to unwind 15 said material from or wind it upon the reel.
5. A device of the character described including a body, and a plurality of clips permanently secured to said body to hold a coil of wire or like material between them- 20 selves and said body, said clips being formed to be forced away from said body to permit the application of a coil thereunder and automatically return to normal position to hold said coil on the body.
- 25 6. A device of the character described including a body, and a plurality of resilient clips permanently secured at one end to said body and adapted to receive between their other ends and said body a coil of wire or 30 like material, said second mentioned ends of the clips being adapted to be sprung away from said body to permit a coil to be ap-

plied thereto and automatically spring into normal position to hold said coil.

7. A device of the character described 35 including a body, and a plurality of clips secured at one end to said body, the other ends of said clips being free from said body to receive a coil of wire or like material between them and said body, the said first men- 40 tioned ends of the clips being adapted to receive the free end of the coil between themselves and said body to clamp the same.

8. A device of the character described 45 including a body, and a plurality of clips secured at one end to said body, the other ends of said clips being free from said body to receive a coil of wire or like material between them and said body, the said first men- 50 tioned ends of the clips being adapted to receive the free end of the coil between themselves and said body to clamp the same, and formed with cutting notches to sever a length of said material from said coil.

9. A device of the character described 55 including a body, and a plurality of clips mounted on said body to hold a coil of wire or like material between themselves and said body, said clips being formed with cutting notches to sever a length of material from 60 the coil.

JOSEPH C. CATLETT.
EDWARD F. NELSON.
